UNITED STATES PATENT OFFICE.

WORTH H. RODEBUSH, OF BERKELEY, CALIFORNIA, ASSIGNOR TO U. S. INDUSTRIAL
ALCOHOL CO., A CORPORATION OF WEST VIRGINIA.

PROCESS OF OBTAINING ALCOHOLS, ETC.

Application filed April 14, 1921. Serial No. 461,302.

To all whom it may concern:

Be it known that I, WORTH H. RODEBUSH, a citizen of the United States, residing at Berkeley, in the county of Alameda and State of California, have invented certain new and useful Improvements in Processes of Obtaining Alcohols, Etc., of which the following is a specification.

My invention relates particularly to a process designed for obtaining alcohols having a high strength and has especial reference to the production of absolute alcohol.

The object of my invention is to provide a process by means of which alcohols having a high strength, that is to say above 95%, and particularly absolute alcohol, may be obtained.

A further object is to obtain this end by distilling an alcohol with a second liquid, as, for example, water, and a third constituent that is miscible with the alcohol but substantially immiscible with the second liquid, as, for example, ethyl acetate, thus obtaining a vapor mixture having different proportions of the constituents than the liquid being distilled and preferably so as to obtain, as a result of the distillation, a constant boiling mixture of the three liquids and as well as an alcohol of a high strength.

Another object is to provide such a process wherein the vapors evolved in the distillation may be condensed and separated into two immiscible liquids containing, respectively, high and low percentages of the third constituent, as by the addition of a further quantity of the second liquid to the condensate.

Again, a further object is to distill these two liquids separately in such a manner as to obtain from one of them the third constituent, as a residue, of substantially 100% strength as well as a condensate comprising said constant boiling mixture and from the other liquid a residue of water together with a condensate of said constant boiling mixture.

Further, the object of my invention is to provide a continuous process in which the aforesaid distillations are conducted simul-

taneously while the distillates are collected together and separated continuously in the manner described.

Further objects of my invention will appear from the detailed description thereof contained hereinafter.

While my invention is capable of being carried out in many different ways, for the purpose of illustration I shall describe only certain ways of carrying out the same hereinafter, and while it is capable of being carried out in connection with many different types of apparatus, I have shown only one type of apparatus for use in connection therewith in the accompanying drawings, in which:

Figure 1 is a diagrammatic representation of an apparatus used in accordance with my invention;

Figure 2 is a vertical section of the measuring receptacle, and

Figure 3 is a section of one of the columns.

For example, in carrying out my invention, assuming that the same is applied to the production of ethyl alcohol having a high strength, as, for example, absolute alcohol from alcohol having a lower strength and incidentally ethyl acetate of 100% strength, 95% strength alcohol is continually fed into a reservoir 1, the feeding of the alcohol being begun as soon as a quantity of ethyl acetate, which is supplied initially to a reservoir 1^a, has passed through the apparatus so as to reach the alcohol fed into the same. The amount of the ethyl acetate introduced is such that at any given time the amounts of the ethyl acetate and 95% alcohol in the system are substantially equal. Thereafter in the operation of the process a constant boiling mixture comprising 83% ethyl acetate, 9% ethyl alcohol and 8% water flows into the reservoir 1^a from the three inlet pipes shown in the drawings and thence into a measuring receptacle 2 and therefrom the mixture flows by a pipe 3 to a mixing coil 4, where the constant boiling mixture is brought into contact with a current of water fed from a water supply tank 5 to a measur-

ing receptacle 6, and thence by a pipe 7 to said mixing coil 4. Each of the measuring receptacles 2 and 6 is comprised of a central inlet pipe 8 connected at the top to a container 9 having laterally directed feeding spouts 10 and 11 beneath which there is located a discharge cylinder 12 surrounding the inlet pipe 8, which cylinder 12 has near the top thereof a slot 13 to carry off the overflow from the measuring receptacle and indicate by the height of the outflowing liquid on a scale 14 at the edge of the slot 13 the rate of flow of the liquid from the measuring receptacle. The rates of flow of the water and the constant boiling solution are regulated so that the volumes of the two liquids fed during a given interval of time are substantially equal. From the mixing coil 4 the liquids pass into a separating tank 15 where an upper layer 16 separates out containing by weight 93% ethyl acetate, 5½% water and 1.5% alcohol, and where a lower layer 17 is formed containing 8% ethyl acetate, 86% water, and 6% ethyl alcohol. These percentages will vary, however, to a considerable extent. The upper layer 16 is drawn off by a pipe 18, and is fed thereby into the side of a column 19 made up of a plurality of pans 20 carrying liquid which overflows from each pan to the next pan below by a series of pipes 21, while the vapors are caused to pass through the bodies of liquid on the pans through liquid sealed bells 22 and pipes 23 leading into the same. Steam is provided for the column 19 by means of a heater 24 located at the bottom thereof comprising tube sheets 25 and 26 carrying tubes 27 and supplied with heating steam by inlet and outlet pipes 28 and 29. From the base of this column there is a drawoff pipe 30 for ethyl acetate having a strength of 100% which leads to a sight glass 31 having a vent pipe 32 leading back to the column 19, and an outlet pipe 33 leading from the bottom thereof. By means of the steam produced in the heater 24, the lower end of the column 19 is maintained at a temperature of substantially 77° C., while the top of said column is maintained at a temperature of approximately 70° C. From the top of the column 19, there is a vapor mixture containing ethyl acetate, water, and alcohol carried over, which is conveyed by a pipe 34 to a dephlegmator 35 cooled by a current of water passing through inlet and outlet pipes 36 and 37, and from which dephlegmator any condensed liquid passes back by a pipe 38 to the tower 19. From the dephlegmator 35, the uncondensed vapors of ethyl acetate, alcohol, and water pass by a pipe 39 to a condenser 40, cooled by a current of water provided with the aid of inlet and outlet pipes 41 and 42, and from which the condensed liquid passes into a

sight glass 43, having a vent 44 and a draw-off pipe 45. From this pipe 45 there is conveyed away a solution containing approximately 83% ethyl acetate, 8% water, and 9% alcohol, which is discharged into the tank 1^a.

The lower layer of liquid 17, is conducted by a pipe 46 to the side of a second column 47 constructed the same as the column 19, except that there is an inlet pipe 48 at the bottom thereof provided with perforations to inject live steam instead of utilizing indirect heat. The steam thus injected maintains the lower end of the column 47 at a temperature of approximately 100° C., and the upper end of the column at a temperature of about 70° C. From the bottom of the column an outlet pipe 49 conveys away the water, and from the top of the column, which is provided with a dephlegmator 50 and a condenser 51, constructed the same as in the case of the column 19, a discharge pipe 52 conveys away the condensed liquid which is approximately the constant boiling solution comprising 83% ethyl acetate, 8% water, and 9% alcohol to the tank 1^a. Near the top of the column 47 where the temperature in the column is substantially 78° C., an outlet pipe 53 is provided for conveying away the excess ethyl alcohol having substantially a 95% strength to the side of a third column 54. The column 54 is constructed the same as the column 19, except that in addition to the inlet pipe 53, there is an inlet pipe 54^a communicating with the pipe 33, which leads from the lower end of the column 19, so as to convey the ester of 100% strength into the side of the column 54. Connected to the pipe 53, furthermore, there is an inlet pipe 53^a leading from the alcohol supply tank 1^a for the 95% alcohol which is continually supplied to the apparatus and which is to be converted into absolute alcohol. The lower end of this column 54 is maintained at a temperature of substantially 78° C., and the top of the tower is maintained at a temperature of about 70° C. From the lower end of this tower there is drawn off alcohol having a high strength, for example, absolute alcohol, by means of a pipe 55, and from the upper end of the tower which is provided with a dephlegmator 56 and a condenser 57, there is conveyed away by means of a pipe 58 a constant boiling solution containing 83% ethyl acetate, 8% water, and 9% ethyl alcohol, which is discharged by said pipe into the tank 1^a.

The process as thus conducted will result in the production of absolute alcohol which is discharged by the pipe 55, ethyl acetate having a strength of 100% which may, if desired, be discharged from the pipe 33, and water which is discharged by the pipe 49.

It will be understood that the amount of

the ethyl acetate fed by the pipe 54 into the side of the tower 54 will be controlled so that the proportions of the absolute alcohol and water discharged from the apparatus will be substantially the same as the proportions of these constituents fed into the apparatus from the tanks 1 and 5.

It will be understood, also, that this process may be conducted with other alcohols such, for example, as propyl alcohol and another third constituent that is not soluble in water but is soluble in the alcohol such as benzol, or any other suitable material that may be used for this purpose. Where propyl alcohol is used propyl acetate could be the third constituent used therewith.

While I have described my invention above in detail, I wish it to be understood that many changes may be made therein without departing from the spirit thereof.

I claim:

1. The process of eliminating a constituent of a binary liquid mixture whose ingredients form a constant boiling mixture, comprising the addition thereto of a third liquid that forms a ternary constant boiling mixture with the other two ingredients and the distillation of the ternary mixture to evolve the ternary constant boiling mixture and leave as a residue the constituent of the aforesaid binary mixture desired to be recovered; adding an additional quantity of the constituent to be eliminated, to the ternary constant boiling distillate, and allowing liquid layers to separate out; distilling each layer to evolve constant boiling mixtures and leave as residues liquids containing as principal constituents respectively the added liquid and the liquid desired to be recovered, and returning these residues to the original mixture undergoing distillation.

2. The process of claim 1 wherein the constant boiling mixtures evolved from the distillation of the layers, are added to the first named constant boiling mixture.

3. The process which comprises distilling a ternary minimum boiling point mixture from a mixture of ethyl alcohol, ethyl acetate and water; adding water thereto and allowing the distillate to separate into two layers; distilling each layer to evolve constant boiling mixtures and adding them to the condensed distillate of the primary distilling process, and obtaining the ethyl acetate and alcohol of low aqueous content as residues of said distillations and returning them to the first liquid mixture undergoing distillation.

4. The process which comprises rectifying a mixture of an ester, water, and an alcohol, containing a larger percentage of the alcohol than would be contained in a constant boiling mixture of these constituents and thereby obtaining the alcohol substantially free from water, and a constant boiling distillate; adding water to the latter and allowing liquid

layers to separate out; distilling the layer richer in ester to evolve a constant boiling mixture and leave a large proportion of the ester as a residue, and adding the latter to the primary mixture undergoing distillation.

5. The process which comprises rectifying a mixture of an ester, water, and an alcohol, containing a larger percentage of the alcohol than would be contained in a constant boiling mixture of these constituents, and thereby obtaining alcohol substantially free from water, rectifying a mixture of an ester, water and an alcohol, containing a larger percentage of the ester than would be contained in a constant boiling mixture of these three constituents so as to obtain some of the ester substantially free from water, feeding the latter into the rectifier in which the alcohol substantially free from water is being obtained, obtaining a constant boiling mixture of the ester, the alcohol and water from such rectification, feeding such constant boiling mixture into contact with a body of water, separating the two bodies of liquid formed to form a liquid layer containing a high percentage of the ester and a liquid layer containing a low percentage of the ester, feeding the first mentioned liquid layer into the rectifier where the mixture containing a higher percentage of the ester is being rectified and distilling the second layer to recover alcohol of low aqueous content, and returning it to the primary mixture undergoing distillation.

6. The process which comprises rectifying a mixture of an ester, water, and an alcohol, containing a larger percentage of the alcohol than would be contained in a constant boiling mixture of these constituents, and thereby obtaining alcohol substantially free from water, rectifying a mixture of an ester, water and alcohol, containing a larger percentage of the ester than would be contained in a constant boiling mixture of these three constituents so as to obtain some of the ester substantially free from water, feeding the latter into the rectifier in which the alcohol substantially free from water is being obtained, obtaining a constant boiling mixture of the ester, the alcohol and water from such rectification, feeding such constant boiling mixture into contact with a body of water, separating the two bodies of liquid formed to form a liquid layer containing a high percentage of the ester and a liquid layer containing a low percentage of the ester, feeding the first mentioned liquid layer into the rectifier in which the mixture containing a higher percentage of the ester is being rectified, rectifying the other liquid layer to recover a more concentrated aqueous alcohol and feeding it into the rectifier in which the alcohol substantially free from water is obtained.

7. The process which comprises rectifying a mixture of an ester, water, and an alcohol,

- containing a larger percentage of the alcohol than would be contained in a constant boiling mixture of these constituents, and thereby obtaining alcohol substantially free from water, rectifying a mixture of an ester, water, and an alcohol, containing a larger percentage of the ester than would be contained in a constant boiling mixture of these three constituents so as to obtain some of the ester substantially free from water, feeding the latter into the rectifier in which the alcohol substantially free from water is being obtained, obtaining a constant boiling mixture of the ester, the alcohol, and water from such rectification, feeding such constant boiling mixture into contact with a body of water, separating the two bodies of liquid formed to form a liquid layer containing a high percentage of the ester and a liquid layer containing a low percentage of the ester, feeding the first mentioned liquid layer into the rectifier in which the mixture containing a higher percentage of the ester is being rectified, rectifying the other liquid layer to recover a more concentrated aqueous alcohol, and feeding it into the rectifier in which the alcohol substantially free from water is obtained, the process being conducted so as to produce a constant boiling mixture of the ester, the alcohol and water in the three rectifications, and bringing the combined constant boiling mixtures from these rectifications into contact with the body of water above specified.
8. The process which comprises distilling a ternary mixture in a column to separate out one ingredient at the bottom thereof and to evolve a constant boiling mixture of the three ingredients, condensing the constant boiling mixture and treating it with an additional quantity of one of the ingredients to form two immiscible liquids, passing one of the latter liquids to a second column, distilling it therein to recover one of said ingredients, and returning the latter to the first column; passing the other liquid to a third column, distilling it therein to recover another of said ingredients, and returning the latter to the first column.
9. The invention in claim 8 wherein the mixture comprises ethyl alcohol, ethyl acetate, and water.
10. The process which comprises distilling a ternary mixture in a column to separate out one ingredient at the bottom thereof and to evolve a constant boiling mixture of the three ingredients; condensing the constant boiling mixture and treating it with an additional quantity of one of the ingredients to form two immiscible liquids, passing the latter to a second and a third distilling column respectively, distilling them therein, condensing the constant boiling mixtures formed and adding them to that of the first column for separation, and recovering from

said columns substantial quantities of two of the ingredients and returning them to the first column.

11. The process which comprises distilling ethyl alcohol, ethyl acetate and water, in a column to separate out the alcohol at the bottom thereof while evolving a constant boiling mixture of the three ingredients; condensing the latter and treating it with an additional quantity of water to form two liquid layers; passing the latter to a second and a third column respectively, rectifying them therein, condensing the constant boiling mixtures formed and adding them to that from the first column, and recovering from said columns substantial quantities of alcohol and ester and returning them to the first column.

12. The process of obtaining absolute alcohol from an aqueous alcohol, which comprises: distilling the latter with a substance miscible with the alcohol but immiscible with water, to form a constant boiling mixture of said substance, alcohol and water, and thereby obtaining an absolute alcohol as a residue; mixing the said constant boiling mixture with water to form liquid layers; separately distilling each layer to recover the said substance and aqueous alcohol; and returning the said substance and aqueous alcohol to the aqueous alcohol undergoing distillation.

13. The process of obtaining an absolute alcohol from an aqueous alcohol, which comprises: distilling the latter with a substance miscible with the alcohol but immiscible with water, to form a constant boiling mixture of said substance, alcohol and water, and thereby obtaining an absolute alcohol as a residue; mixing the said constant boiling mixture with water to form liquid layers; separately distilling each layer to evolve ternary constant boiling mixtures and to recover a substantial quantity of the said substance and aqueous alcohol; and returning the said substance and aqueous alcohol to the first named aqueous alcohol.

14. The invention in claim 13 wherein the constant boiling mixtures evolved from the secondary distillations are added to the first constant boiling mixture for subsequent separation.

15. The process of obtaining absolute alcohol from aqueous ethyl alcohol which comprises: distilling the latter with ethyl acetate to form a constant boiling mixture of ester, alcohol and water and thereby obtaining absolute alcohol as a residue; mixing the said constant boiling mixture with water to form liquid layers; separately distilling each layer to recover a substantial quantity of the ester and aqueous alcohol; and returning the ester and alcohol to the ethyl alcohol undergoing distillation.

16. The process of obtaining absolute alco-

hol from aqueous ethyl alcohol, which comprises: distilling the latter with ethyl acetate to form a constant boiling mixture of ester, alcohol and water, and thereby obtaining absolute alcohol as a residue; mixing the said constant boiling mixture with water to form liquid layers, separately distilling each layer to evolve ternary constant

boiling mixtures and to recover pure ester and aqueous alcohol; and returning the ester and alcohol to the ethyl alcohol undergoing distillation.

In testimony that I claim the foregoing, I have hereunto set my hand this 5th day of April, 1921.

WORTH H. RODEBUSH.
